UNITED STATES PATENT OFFICE.

JULIUS H. HILDEBRANDT, OF CLEVELAND, OHIO.

OIL BURNER.

Application filed September 15, 1923. Serial No. 662,804.

To all whom it may concern:

Be it known that I, JULIUS H. HILDEBRANDT, a citizen of the United States, residing at Cleveland, in the county of Cuyahoga and State of Ohio, have invented a certain new and useful Improvement in an Oil Burner, of which the following is a full, clear, and exact description, reference being had to the accompanying drawings.

10 This invention relates to liquid fuel burners particularly those wherein the fuel is fed by gravity while a forced draft supplies air for supporting combustion.

One of the difficulties heretofore experienced in the operation of oil burners operating under forced draft is the fact that the intense heat burns out parts of the burner in a comparatively short time. This is especially noticeable in types of burners 20 wherein the air is led upwardly through suitable manifolds, and then is directed downwardly and outwardly while being mixed with the fuel. The air manifolds are thus directly in the path of the flame and hence any cracks or fissure which develop in the castings cause a leakage of air, and hence reduce the efficiency of the burner.

One of the objects of my invention therefore, is the provision of an oil burner which 30 is so constructed that sufficient air for effecting complete combustion may be obtained by forced draft without necessitating the positioning of any of the parts directly in the zone of highest temperature. In this connection my invention contemplates the provision of a liquid fuel burner which may be readily inserted within existing furnaces, for enabling the introduction of sufficient air without necessitating extensive changes 40 in the construction of the furnace.

A further object of my invention is the attainment of a liquid fuel burner which is extremely simple in construction, which has few parts upon which machine work must 45 be done, and which may be quickly assembled within the restricted area in which the burner is to be operated.

Still another object of my invention is the arrangement of means for preventing the flow of excess oil into the ashpit in the event of the flame being extinguished while the fuel is turned on.

The preferred means for carrying out my invention is illustrated in the accompanying 55 drawings, while the essential characteristics

of my invention are summarized in the claims.

In the drawings, Fig. 1 is a vertical section through a portion of the furnace showing my invention installed therein; Fig. 2 is a similar section showing some of the burner parts removed from their normal position to illustrate the manner of assembly; Fig. 3 is a perspective view showing the upper end of the air manifold; Fig. 4 is a section on an enlarged scale of a portion of the apparatus shown in Fig. 1; Fig. 5 is a section taken on the line 5—5 in Fig. 1, and Figs. 6 and 7 are sectional details on an enlarged scale taken at right angles to each other through the baffle plate.

My invention is illustrated as applied to an oil burner and accordingly I have shown the burner within a furnace, the walls of which are indicated at 10, and the base of 75 which is illustrated as 11. A grate 12 is disposed across the top of the base and represents any suitable or convenient form of grate. An opening 13 in the base illustrates the opening for an ashpit door, while an opening 14 in the furnace wall illustrates the opening for a fire box door. The burner is adapted to be positioned upon the grate and is arranged to be inserted through the fire box door opening. The conduits 80 through which the fuel and air are conducted are preferably arranged to be led through the ashpit door opening.

The burner illustrated represents the down draft type. The fuel is arranged to 90 enter the burner through a conduit 20 preferably by gravity from whence it is caused to drop into a distributor 21, which is illustrated as having a receptacle or pocket 22 directly beneath the end of the 95 conduit 20. The fuel is then arranged to be led from the pocket 22 through laterally extending passageways 23 which terminate in a common basin or annular passage- 100 way 24, adjacent the base of the distributor.

Suitable conduits 25 are shown as being spaced about the base of the distributor, and arranged to conduct the fuel from the basin. The fuel is thus caused to drop upon a baffle 26 indicated as a conical member having the base portion thereof curved upwardly and outwardly, to provide an annular 105 receptacle 27 in which the fuel may collect.

The air for supporting combustion may be led into the burner through a supply pipe 110

30 which is arranged to communicate with a conduit 31. The upper end of the conduit may support a hood 32, wherefore suitable passageways 33 are provided to permit the 5 egress of air into the furnace. A transverse wall 34 within the hood deflects the air downwardly between the conduit and hood thereby causing it to be impinged with the fuel upon the conical surface of the baffle, 10 and then to be deflected laterally into the furnace by a baffle plate 35. Thus air and fuel are forced together downwardly, and then outwardly, into the furnace chamber.

The hood preferably comprises a hollow 15 casting having a transverse wall 34 forming a continuation of the distributor 21, and having the side walls thereof spaced from the conduit 31. The transverse wall is also shown as having a portion 36 which projects 20 into the air conduit and provides a snug fit therewith, whereby the hood is positioned automatically when placed thereon. The necessity for proper positioning is occasioned 25 by reason of the fact that the oil flowing downwardly from the receptacle 22 should flow evenly into the passageways 23 to insure uniform distribution of the fuel upon the baffle 26. As a further aid to permit accurate positioning of the hood without necessitating adjustment, I have shown the passageways or notches 33 in the air conduit as 30 being three in number, wherefore the hood will rest evenly upon the top of the conduit. The walls of the hood are preferably ex- 35 tended above the transverse wall 34 and ar- ranged to receive a closure 40 which may be attached thereto as by securing members 41. The conduit 20 is then arranged to enter the center of the closure.

40 The air conduit preferably comprises a tubular casting having an enlargement thereon to provide the conical baffle 26. The lower end of the air conduit preferably ex- 45 tends through registering openings in the base 46 and baffle 35 and projects into the ashpit through the center of the grate. As shown, a recess 45 is provided to facilitate admission of the supply pipe 30.

50 The air conduit may be supported upon the baffle 35 which in turn is shown as resting upon a base 46. This base may be a hollow casting which is arranged to rest directly upon the grate and to serve as a 55 means for insuring the proper height of the flame within the furnace. A further purpose for the base 46 is to distribute the weight of the burner evenly over the grate wherefore proper adjustment may be made by the use of shims between the base and the grate to insure level setting for the distributor.

60 The baffle 35 is illustrated as a dish-shaped member, or plate which projects outwardly from the base of the baffle 26 and is sup- 65 ported upon the base 46. In the preferred

form the baffle plate 35 has a hub 50 which enters a recess 51 and thereby serves to position the air conduit and to maintain it in adjusted relationship therewith. Suitable spaced ribs 52 may be disposed on the 70 underside of the baffle plate for reinforcing purposes.

To prevent the over-flow of fuel into the ashpit in the event of the flame being extinguished while the fuel is turned on, I 75 have illustrated a conduit 55, as attached to the baffle plate 35 intermediate the hub and the outer marginal edges thereof. The lower end of this conduit leads into an over-flow receptacle 56 from which suitable mechanism (not shown) may be provided to shut off the fuel supply when the level of fuel in the receptacle reaches a predetermined height. The point at which the conduit 55 leads from the baffle plate is beneath a horizontal plane passing through the top of the hub 50, wherefore any excess fuel is prevented from leaking between the plate and the air conduit, and thence overflowing into the ashpit. Thus the hub 50, provides a receptacle while the conduit 55 comprises an outlet for surplus fuel before the fuel is allowed to flow over the edge of the plate or between the plate and the air conduit. 80 To prevent filling of the passageway through the conduit 55, such as by unconsumed carbon which may be deposited upon the plate 35, I have shown means for protecting the opening leading to the passageway. The preferred means is illustrated as a cover 57 which is preferably integral with the plate. The cover surrounds the opening leading to the conduit on three sides as at 85 57, 58 and 59, respectively, thus leaving the outer side open to permit the entrance of fuel.

To permit automatic operation of a burner made in accordance with my invention, I have shown a means for maintaining a pilot light in operation which light will not be extinguished by the rush of air due to the forced draft. This pilot is operated by gas which may be led into the burner through a conduit 60 which is also shown as entering the furnace through the opening in the ashpit door. A conduit 62 housed within the air conduit 31 communicates at one end thereof with the fuel line 60, and at the other end with a conduit 65 which leads to a 90 burner 64. This burner is shown in detail and claimed in my copending application, Serial Number 639,239, filed May 16, 1923.

The conduit 62 is preferably cast integral with the air conduit wherefore the conduit 60 may be readily disconnected, to permit dismantling of the burner. This manner of fuel connections enables the pipe connections to be made in the ashpit where sufficient space is available for such work.

Referring now more specifically to Fig. 2,

it will be seen that the various fluid conduits may all be led into the furnace through the ashpit door opening while the various parts of the burner above the grate may be inserted one at a time through the furnace door opening. In assembling the burner, the base 46 is positioned on the grate whereupon the plate 35 is placed over the base, whence the air conduit together with the 5 pilot burner attached thereto, is passed through registering openings adjacent the midportion of the plate 35 and the base 46. The conduit is thus lowered until the hub 50 enters the recess 51, whereupon the hood 10 32, having the conduits 25 previously attached thereto is placed over the air conduit in such manner that the projection 36 extends therein. Thereupon, connections are 15 made in the fuel line, while the air supply pipe 30 is forced upwardly into engagement 20 with the air conduit.

To start a burner made in accordance with my invention, the oil is turned on until the receptacle 27 is practically filled, whereupon 25 the oil is ignited either by the pilot light or by any other suitable means. The oil is thus burned until the baffle 26 is sufficiently hot to vaporize the oil which subsequently flows down the conduits 25. Thereupon, 30 the air is turned on and the flow of oil is regulated to the desired degree of heat.

In view of the foregoing description it will be evident that my invention provides a liquid fuel burner which is very simple in 35 construction and which may be readily inserted through the usual fire box door opening, and be quickly assembled without necessitating extensive changes in the construction of the furnace. Moreover, a burner 40 made in accordance with my invention has few parts which are subjected to intensive heat of the flame, wherefore the burning out of the essential parts is obviated.

I claim:

45 1. In a liquid fuel burner the combination with an upwardly extending air conduit, of a laterally deflecting baffle outside said conduit, a conical baffle disposed above the first mentioned baffle, a hood disposed 50 above the conduit and extending downwardly over the sides thereof to deflect downwardly air which is ejected from the conduit, a liquid fuel distributor associated with the hood, a centrally located pocket 55 within the distributor, spaced passage-ways leading outwardly and downwardly from the pocket, said passage-ways terminating beyond the edges of air conduit, whereby fuel is caused to intermingle with air in the 60 region intermediate the hood and the outer walls of the conical baffle, and a fuel supply conduit arranged to conduct liquid fuel into said pocket.

65 2. In a liquid fuel burner the combination with an upwardly extending air con-

duit, of a conical baffle surrounding the conduit and having a trough at the base thereof, a liquid fuel distributor positioned on the conduit and having a centrally located pocket, there being passage-ways extending radially from the pocket and terminating beyond the edges of the conduit, a liquid fuel supply conduit arranged to convey liquid fuel to the pocket, said passage-ways being arranged to conduct liquid fuel from the pocket downwardly over the outer walls of the air conduit and onto the conical baffle, a hood associated with the distributor and functioning to effect commingling of air and liquid fuel, said hood extending downwardly below the upper end of the air conduit, a pilot light disposed beneath the distributor and intermediate the air conduit and hood, and a supply conduit for the pilot light extending through the air conduit.

3. In a liquid fuel burner, the combination with a support, of a substantially cylindrical member having an intermediate dividing wall, the wall having a portion thereof engaging the support in such manner as to hold the peripheral position of the member in spaced relation to the support, said wall having a pocket adjacent the center thereof and an annular groove adjacent the periphery thereof, spaced passageways leading from the pocket to the groove, a fuel inlet conduit arranged to convey fuel into said pocket and spaced passageways leading downwardly from the groove for conveying the fuel intermediate the support and the peripheral portion of said member.

4. In a liquid fuel burner, the combination with a support, of a substantially cylindrical member, said member having a transverse wall adapted to engage a support for positioning the member thereon, said wall having an extension adjacent the mid-portion thereof, said extension having a pocket in the top thereof, a closure for said member, a fuel inlet conduit leading to the closure to conduct fuel into said pocket, and a plurality of spaced conduits leading downwardly from the pocket to conduct fuel between the support and the walls of said member.

5. In a liquid fuel burner, the combination with an air conduit having a fuel conduit housed therein, a burner attached to the upper end of said fuel conduit to provide a pilot light, a hood resting on the air conduit and having the walls thereof disposed in spaced relation to said burner, a liquid fuel supply conduit associated with the air conduit, and a liquid fuel distributor arranged to convey liquid fuel downwardly and intermediate the air conduit and the hood, whereby the liquid fuel and air are commingled in the region of said burner.

6. In a liquid fuel burner the combination with a vertically extending air conduit, of a fuel distributor positioned on said conduit, a

hood enclosing said distributor, a fuel inlet conduit extending through the air conduit and terminating beneath the distributor and intermediate the walls of the air conduit and the hood, a conical baffle associated with the air conduit and disposed beneath the distributor, said baffle being adapted to deflect laterally fuel and air flowing downwardly between the air conduit and the hood, and 5 a second baffle disposed beneath the first mentioned baffle and adapted to deflect further laterally the commingled air and fuel. 10 7. In a liquid fuel burner, the combination with a base having an opening disposed adjacent the midportion thereof, a dish-shaped baffle having an opening adapted to register with an opening in the base, an air conduit extending through said opening and having a shoulder in engagement with the 15 baffle, a conical baffle associated with the conduit and disposed above the first-mentioned baffle, a fuel distributor disposed above said baffles, and a fuel inlet conduit leading to said distributor. 20

8. In a liquid fuel burner, the combination with a dish-shaped baffle, of a conical baffle disposed thereabove, an air conduit leading upwardly through the baffles, means for deflecting air downwardly from said conduit, a fuel inlet conduit, and means for distributing fuel uniformly from said fuel conduit intermediate the walls of said air conduit and said air deflecting means. 25

9. In a liquid fuel burner, the combination with a laterally deflecting baffle, of a substantially conical baffle disposed thereabove, an air conduit leading upwardly through the conical baffle, a member associated with the conduit for deflecting air downwardly over said baffles, a fuel inlet conduit, and means associated with said member for distributing fuel uniformly intermediate said member and said air conduit whereby the air and fuel commingle when deflected by said conical baffle. 30 35 40 45

In testimony whereof, I hereunto affix my signature.

JULIUS H. HILDEBRANDT.
